[57] CLAIM

The ornamental design for a carrying case for a video cassette recorder, as shown and described.

DESCRIPTION

FIG. 1 is a perspective view of a carrying case for a video cassette recorder showing my new design;

FIG. 2 is a top plan view thereof;

FIG. 3 is a front elevational view thereof, the rear being a mirror image;

FIG. 4 is a bottom plan view thereof; and

FIG. 5 is a right side elevational view thereof, a left side being a mirror image.
